UNITED STATES PATENT OFFICE

2,047,712

UMBRELLA

John A. H. Siers, Jersey City, N. J.

Application November 29, 1935, Serial No. 52,049

12 Claims. (Cl. 135—37)

This invention relates to umbrellas or parasols of the collapsible type in which a marked reduction is effected in the overall length of the umbrella, when closed, so that it may be conveniently carried in the pocket, handbag or suitcase.

The subject matter of the present application is, in part, a continuation of my prior application for patent Serial No. 752,197, filed November 9, 1934, and relates more particularly to the latch means, whereby the telescopically connected sections of the umbrella staff are retained in telescoped or extended relation to each other.

A more particular object of the invention resides in the provision of a yieldable latch element mounted within the inner staff section and a pin mounted on the end of the outer staff section, and having means at its inner end adapted to coact with said latch element.

In one embodiment of the invention, the latch device may be provided with spaced parts for coacting engagement with spaced means on one of the staff sections, whereby said staff sections are retained in telescoped or extended relation to each other.

In another embodiment of my invention, the pin carried by the outer staff section may be manually moved to cooperate with the latch element and move the latter to released position, whereby the inner staff section may be extended from the outer section.

It is a further general object of my invention to provide a latch means for the sectional umbrella staff which is simple, durable and inexpensive in its construction, as well as efficient and reliable in practical operation.

With the above and other objects in view, the invention consists in the improved umbrella or parasol, and in the form, construction and relative arrangement of its several parts as will be hereinafter more fully described, illustrated in the accompanying drawings and subsequently incorporated in the subjoined claims.

In the drawings, wherein I have illustrated several simple and practical embodiments of the invention and in which similar reference characters designate corresponding parts throughout the several views:

Fig. 1 is a fragmentary vertical section illustrating one embodiment of the invention, and showing the umbrella open and ready for use.

Fig. 2 is a similar vertical section on an enlarged scale showing the umbrella closed and the staff sections in telescoped relation.

Fig. 3 is a vertical sectional view similar to

Fig. 1, illustrating a modified embodiment of the invention, and

Fig. 4 is a sectional view corresponding to Fig. 2 of the modified form of the device.

Referring in detail to the drawings, the umbrella staff as herein shown, embodies upper and lower sections 5 and 6 respectively, of thin walled metal tubing. Preferably, the lower section 6 is telescoped within the upper section 5, suitable means being provided to limit the outward extension of the section 6 from the staff section 5.

Upon the upper end of the outer staff section 5, a sleeve 7 is suitably fixed and a pin 8 is mounted in the end of this sleeve, for a purpose to be later explained.

The usual runner 9 is vertically slidable on the staff section 6 and carries a latch element 10 to releasably engage at one of its ends in an opening in the wall of the staff section 5 to retain said runner at the limit of its outward movement. To the sleeve 7 and the runner 9, the parts of the umbrella frame are connected. This frame, herein generally indicated at 11, has a covering of elastic sheet material 12, suitably applied thereto. For a more particular description of this collapsible frame and its covering, reference may be had to my pending application for patent above referred to.

Within the staff section 6, a slotted or grooved member 13 is suitably fixed. As shown in Figs. 1 and 2 of the drawings, a latch member in the form of a bowed leaf spring 14 is connected at one of its ends to the member 13 and at its other free end is provided with an angularly offset part 15 and adjacent thereto with the convex stud 16 for bearing engagement against the inner wall of the staff section 6. Intermediate of its ends, a lug 17 is fixed to the latch element 9 to project outwardly through an opening 18 in the wall of the staff section 6 when the staff sections are in telescoped relation. This lug is received in a recess 19 in the lower end of the wall of the staff section 5 to releasably hold the section 6 in its extended position and prevent relative rotational movement of the latch sections.

The inner end of the screw or pin 8 is formed with a reduced neck 20 and conical terminal 21, which provides an angular shoulder 22. Thus, it will be understood, that when the staff section 6 is moved into the section 5 until its end abuts against the end of the sleeve 7, the angular offset 15 at the free end of the latch element 14 first engages the conical end 21 of the pin 8 and yieldably moves said latch element from its normal

position until said end portion 15 of the latch element snaps over the shoulder 22 of said pin. The stud 16 bearing against the wall of the staff section 6 insures adequate tension of the spring to 5 resist unintentional outward movement of said staff sections.

In opening the umbrella, the staff section 6 is first pulled outwardly, the end 15 of the latch element 14 yielding in response to such pull and 10 being disengaged from the shoulder 22 of the pin 8. At the limit of the outward movement of the staff section 6, the lug 17 on the latch element is projected outwardly into the recess 18 in the end of the staff section 5, thus preventing unintentional inward movement of the staff section 6 15 and locking the staff sections against relative rotation.

In Figs. 3 and 4 of the drawings, I have shown a slightly modified form of the invention in which 20 the member 13' is mounted in the staff section 6 at a point adjacent to its upper end. The latch element 23 is mounted in the slot or groove of the member 15 for pivotal movement upon the pin 24. In this case, said latch element is in the form of 25 a lever (one end of which projects below the member 13' and has an angular locking finger 25 adapted to be projected outwardly through registering openings 26 and 27 respectively in the staff sections 5 and 6 by means of the spring 28 30 which is connected at one of its ends to the latch lever and has bearing engagement at its other end against the wall of the staff section 6. Preferably, this spring 28 in spaced relation to its point of attachment to the latch lever has bearing contact upon a stud 29 fixed to said lever, so 35 that said spring will be properly tensioned when the lever is displaced from its normal position.

At its other end, the latch lever 23 is formed with an obliquely inclined lug 30, with which the 40 conical end 31 of pin 32 is adapted to coact. In this case, the pin 32 is carried by a separate cap member 33 threaded through the outer end of the sleeve 7 and which cap member also serves to clamp the central portion of the umbrella cover 45 12 against the said sleeve. The pin 32 extends through a recess in said cap member and is surrounded by the coil spring 34 which bears against the head of the pin and yieldably urges the same outwardly to its normal position.

50 In spaced relation to its lower end, the wall of the staff section 5, in this last described form of the device, is provided with an opening 35, with which the opening 26 of the staff section 5 is adapted to register when the latter section is extended outwardly to its limit from the section 5. The angular member 25 of the latch lever is then projected outwardly by the spring 28 through these registering openings, thereby locking the two staff sections against any longitudinal or 55 rotative movement.

In closing the umbrella, the end 25 of the latch lever is pressed inwardly through the opening 35 and the staff section 6 is forced longitudinally into the section 5. When the end of said section 6 60 abuts against the inner end of the cap member 33, the opening 26 will be in registration with the opening 27 and the angular or inclined lug 30 of the latch lever will be opposed to the conical end 31 of the pin 32, thus limiting the outward projection of lug 25 by the spring 28 through the registering openings, so that there will be very little projection of the end of this latch lever beyond the outer surface of the staff section 5 to thereby obviate the possibility of the accidental 65 movement of the latch lever to its release position.

Therefore, in this form of the invention, unlike that first described, the latch lever operates to also hold the two staff sections against relative rotation when in their telescoped positions.

In order to move the lever 23 to its release 5 position, pressure is applied to the end of pin 32 with the finger, thereby compressing spring 34 and causing the conical end 31 of said pin to coact with the inclined lug 30 thereby rocking the latch lever and moving its angular end 25 inwardly 10 through the opening 27 of the staff section 5 against the resistance of the spring 28. Staff section 6 may then be moved outwardly to its extended position from section 5, as seen in Fig. 4 15 of the drawings.

From the foregoing description in connection with the accompanying drawings, the construction, manner of operation and several advantages of the described embodiments of my invention will be clearly and fully understood. It will be 20 seen that either alternative provides a latch means for the telescoping staff sections, which is simple, reliable and efficient in its functional operation, as well as durable and inexpensive in its construction. The described constructions, as to 25 the form and relative arrangement of the several elements, are more or less suggestive, though in actual use, I have found the same to be preferable. However, it is to be understood that in the practical application and development of my present invention, I reserve the privilege of resorting to all such legitimate variations in the details of 30 my present disclosure as may be fairly comprehended within the scope of the appended claims.

I claim:

1. In an umbrella, an extensible staff comprising outer and inner telescopically connected sections, means for releasably holding said staff sections in telescoped relation, including a latch element carried by the inner section, and means 40 mounted on one end of said outer staff section coacting with said latch element when the staff sections are telescoped and controlling movement of said element to its latching position.

2. In an umbrella, an extensible staff comprising outer and inner telescopically connected sections, means for releasably holding said staff sections in telescoped relation including a latch element carried by the inner section and yieldingly held in a normal position relative thereto, and a 50 pin mounted on one end of said outer staff section, said pin and latch element having coacting parts controlling movement of said element to its latching position when the staff sections are telescoped.

3. In an umbrella, an extensible staff comprising outer and inner telescopically connected sections, a frame supporting sleeve mounted on one end of the outer staff sections, means for releasably holding said staff sections in telescoped relation, including a latch element carried by the inner section and yieldingly held in a normal position relative thereto, and a pin extending axially through the outer end of said sleeve, the inner end of said pin having means to coact with said latch 60 element when the staff sections are telescoped and control the movement of said element to its latching position.

4. In an umbrella, an extensible staff comprising outer and inner telescopically connected sections, a latch device carried by one of said sections, and spaced means on the other staff section with which different parts of said latch device coact to retain said staff sections in telescoped or extended relation to each other.

5. In an umbrella, an extensible staff comprising outer and inner telescopically connected sections, a yieldable latch element mounted within the inner staff section and having means to coact with means at one end of the outer staff section and retain said sections in extended position, a pin mounted on the other end of said outer staff section, and said latch element having additional means coacting with said pin when the staff sections are telescoped to control the movement of said element to its latching position, whereby said staff sections are retained in telescoped relation.
10. In an umbrella, an extensible staff comprising outer and inner telescopically connected sections, a sleeve on one end of the outer staff section, a member extending inwardly from one end of said sleeve having a conical terminal providing an angular shoulder, a leaf spring fixed at one end within the other staff section, having a part intermediate of its ends to coact with means on the other end of the outer staff section and retain said sections in extended relation to each other, and said spring having means at its opposite end to engage the conical end of said member and coact with said shoulder to thereby retain the staff sections in telescoped relation.
15. In an umbrella, an extensible staff comprising outer and inner telescopically connected sections, a sleeve on one end of the outer staff section, a member extending inwardly from one end of said sleeve having a conical terminal providing an angular shoulder, a leaf spring fixed at one end within the other staff section, having a part intermediate of its ends to coact with means on the other end of the outer staff section and retain said sections in extended relation to each other, and said spring having means at its opposite end to engage the conical end of said member and coact with said shoulder to thereby retain the staff sections in telescoped relation.
20. In an umbrella, an extensible staff comprising inner and outer telescopically connected sections, a latch lever pivotally mounted within the inner staff section, said staff sections having means with which one end of said lever is adapted to coact when said sections are in telescoped relation, to hold the sections against relative longitudinal or rotative movement, and manually operable means mounted on the outer staff section and adapted to coact with the other end of said latch lever to move said lever to its release position.
25. In an umbrella, an extensible staff comprising inner and outer telescopically connected sections, a latch lever pivotally mounted within the inner staff section, said staff sections having means with which one end of said lever is adapted to coact when said sections are in telescoped relation, to hold the sections against relative longitudinal or rotative movement, and manually operable means mounted on the outer staff section and adapted to coact with the other end of said latch lever to move said lever to its release position.
30. In an umbrella, an extensible staff comprising inner and outer telescopically connected sections, a latch lever pivotally mounted within the inner staff section, said staff sections having means with which one end of said lever is adapted to coact when said sections are in telescoped relation, to hold the sections against relative longitudinal or rotative movement, and manually operable means mounted on the outer staff section and adapted to coact with the other end of said latch lever to move said lever to its release position.
35. In an umbrella, an extensible staff comprising inner and outer telescopically connected sections, a latch lever pivotally mounted within the inner staff section, said staff sections having means with which one end of said lever is adapted to coact when said sections are in telescoped relation, to hold the sections against relative longitudinal or rotative movement, and manually operable means mounted on the outer staff section and adapted to coact with the other end of said latch lever to move said lever to its release position.
40. In an umbrella, an extensible staff comprising inner and outer telescopically connected sections, a latch lever pivotally mounted within the inner staff section, said staff sections having openings adapted to register when the sections are fully telescoped, said lever having means at one end coacting with said openings to prevent relative longitudinal or rotative movement of the staff sections, a cap member on one end of the outer staff section, and a manually operable pin axially movable through the cap member engag-
- ing the other end of said lever to limit movement of the same to latching position, and said pin being operable to actuate said lever to its release position.
45. In an umbrella, an extensible staff comprising inner and outer telescopically connected sections, a latch element movably mounted on the inner staff section and adapted to coact with means on said staff sections to retain the latter in telescoped relation, and means carried by the outer staff section coacting with said latch element to control the movement of said element to its latching position.
50. In an umbrella, an extensible staff comprising inner and outer telescopically connected sections, a latch member movably mounted on the inner staff section adapted to coact with means on said staff sections to retain the same in telescoped relation, and means movably mounted on the outer staff section to coact with said latch element and control the movement of said element to its latching position, said means being manually operable to actuate said element to its release position.
55. In an umbrella, an extensible staff comprising inner and outer telescopically connected sections, a latch lever pivotally mounted intermediate of its ends on the inner staff section, said lever having a terminal part to coact with means on said staff sections and retain the latter in telescoped relation, and means mounted on the outer staff section adapted to coact with the opposite end of said lever to control the movement of said lever to its latching position.
60. In an umbrella, an extensible staff comprising inner and outer telescopically connected sections, a latch lever pivotally mounted intermediate of its ends on the inner staff section, said lever having a terminal part on one end coacting with means on the staff sections to retain the latter in telescoped relation, a pin movably mounted on the outer staff section, said lever at its other end having a terminal part coacting with said pin to control movement of the lever to its latching position, and said pin being manually operable to coact with the latter terminal part of the lever to move said lever to its release position.

JOHN A. H. SIERS.
